J. S. ARNDT

PIPE CLEANER

Filed April 5, 1922

FIG. 5

INVENTOR.
John S. Arndt.

John S. Arndt
ATTORNEY.

UNITED STATES PATENT OFFICE.

JOHN S. ARNDT, OF DENVER, COLORADO.

PIPE CLEANER.

Application filed April 5, 1922. Serial No. 549,807.

To all whom it may concern:

Be it known that I, JOHN S. ARNDT, a citizen of the United States, residing at Denver, in the county of Denver and State of Colorado, have invented certain new and useful Improvements in Pipe Cleaners, of which the following is a specification.

My invention relates to tobacco pipe cleaners and its object is to provide a device 10 of very simple construction which when turned inside the bowl of a tobacco pipe, will in one operation, loosen all residue of the burnt tobacco usually adhering in the bottom of the bowl after the pipe has been 15 smoked, and withdraw the loosened matter through the mouth of the same, and which at the same time will even and remove the incrustation on the interior surface of the bowl.

Another object of the invention is to provide a tool of the above described character which can be folded when not in use and may be carried loose in the pocket or at the 20 end of a watch or key-ring chain.

With the above objects in view my invention consists in the novel construction illustrated in the accompanying drawings in the various views of which like parts are similarly designated and in which—

Figure 1 represents an elevation of my improved pipe cleaner in the open position;

Figure 2, an edge view of the same, looking in the direction of the arrow 2 in Figure 1;

Figure 3, an elevation of the device in its closed position;

Figure 4, a transverse section of the blade of the cleaner taken on the line 4—4, Figure 1 and drawn to an exaggerated scale, and

Figure 5, a sectional elevation of the bowl of a tobacco pipe showing the working end of the cleaner in its operative position with relation thereto.

Referring more specifically to the drawings, my improved pipe cleaner consists of a flat blade 5 pivoted as at 7 at an end of a two leaved handle 6 which when the device is not in use, encloses the major portion of the blade and protects the cutting edge thereof.

The handle which in the form shown in the drawings consists of two leaves 13 and an interposed distance slug 14 at an end thereof, is curved in conformity with the blade as will hereinafter be described, and

provided with an aperture 8 for its attachment to the chain of a watch or key-ring.

The blade which is preferably made of tempered steel, is of a substantially uniform width slightly less than the inside diameter of a pipe bowl of average size. The blade is sharpened to provide a cutting or scraping edge 9 and its end is rounded as at 10 in approximately semi-circular form to fit the bottom portion of the bowl of a tobacco pipe in which it is inserted.

The rounded end portion of the blade is furthermore bent at the cutting edge of the same in an auger twist which when the tool 70 is turned inside the pipe bowl, withdraws the loosened matter toward the mouth thereof.

In the operation of my improved pipe cleaner, the blade is inserted in the pipe 75 bowl as illustrated in Figure 5, and turned therein about a longitudinal axis with its cutting edge engaging with the interior surface of the bowl.

The rounded and twisted end-portion of 80 the blade loosens and removes the charred and moistened residue of the burnt tobacco which usually remains in the bottom of the bowl after the pipe has been used and the cutting edge of the blade at the same time, 85 evens the carbon incrustation on the inner surface of the bowl and loosens adherent ashes and tobacco.

When subsequently the blade is withdrawn from the bowl, it carries with it all 90 the loosened matter owing to the auger twist of its rounded end portion.

The auger twist furthermore prevents the loosened matter from entering the stem of the pipe and the uniform width of the blade 95 prevents undercutting of the incrustation, as occurs in the use of pipe cleaners at present on the market, and permits of the removal of all or any part of the incrustation as may be desired.

A single turn of the blade inside the pipe bowl produces a smooth clean and even surface and frees the opening in the bottom of the bowl from any obstructive matter which if permitted to remain would hinder 105 the free passage of the smoke to the stem of the pipe.

It will be apparent that my improved pipe cleaner thus performs in one operation 110 the functions of two or more other tools ordinarily required to thoroughly clean the bowl of a pipe.

What I claim and desire to secure by Letters Patent is:

1. A tobacco pipe cleaner comprising a flat blade having a scraping edge and a rounded end which is bent at said edge into an auger twist.

2. A tobacco pipe cleaner comprising a blade of substantially uniform width, having a scraping edge and a rounded end which is bent at said edge into an auger twist.

3. A tobacco pipe cleaner comprising a blade having a scraping edge and an end of substantially semi-circular contour which is bent at said edge into an auger twist.

4. A tobacco pipe cleaner comprising a flat blade of substantially uniform width having a scraping edge and an end of substantially semi-circular contour which is bent at said edge into an auger twist, 20

5. A tobacco pipe cleaner comprising a sharp-edged blade having its end rounded to fit the concavity at the bottom of a pipe bowl at one side thereof, and bent into an auger twist to provide a scoop for the withdrawal of loose matter from the bowl. 25

In testimony whereof I have affixed my signature.

JOHN S. ARNDT.
